US00D745622S

(12) **United States Design Patent**
Zusman

(10) **Patent No.:** **US D745,622 S**
(45) **Date of Patent:** **** Dec. 15, 2015**

(54) **GUN STOCK**

(71) Applicant: **Nisim Zusman**, Ein Ayala (IL)

(72) Inventor: **Nisim Zusman**, Ein Ayala (IL)

(**) Term: **14 Years**

(21) Appl. No.: **29/491,009**

(22) Filed: **May 15, 2014**

(51) LOC (10) Cl. **22-01**

(52) U.S. Cl.

USPC **D22/108**

(58) **Field of Classification Search**

(57) **CLAIM**

The ornamental design for a gun stock, as shown and described.

DESCRIPTION

FIG. 1 is a perspective view of a gun stock in accordance with my new design;

FIG. 2 is a front left perspective view of the gun stock of FIG. 1;

FIG. 3 is a front view of the gun stock of FIG. 1;

FIG. 4 is a rear view of the gun stock of FIG. 1;

FIG. 5 is left side view of the gun stock of FIG. 1;

FIG. 6 is a right side view of the gun stock of FIG. 1;

FIG. 7 is a top view of the gun stock of FIG. 1; and,

FIG. 8 is a bottom view of the gun stock of FIG. 1.

All portions shown in broken lines are environmental and illustrative only and form no part of the claimed design.

1 Claim, 6 Drawing Sheets
